UNITED STATES PATENT OFFICE.

CARL L. STURGIS, OF BROCKTON, MASSACHUSETTS, ASSIGNOR TO FITZ-EMPIRE DOUBLE PIVOT LAST COMPANY, OF AUBURN, MAINE, A CORPORATION OF MAINE.

HINGE LAST.

Application filed March 26, 1928. Serial No. 264,933.

This invention relates to impositive lock hinge lasts for use in making boots and shoes.

In hinge lasts of this type relative turning movement of the forepart and heel part 5 around a pivotal center is resiliently opposed by a force which increases during the first part of last-collapsing movement at least. The resilient resistance in some such lasts diminishes after the collapsing movement has proceeded 10 to a substantial extent, while in others it increases steadily up to the limit of collapse, thus tending to restore the last automatically to extended position when collapsed. Such a last is shown in United States Letters Patent 15 No. 784,149, granted March 7, 1905, on the application of A. G. Fitz.

It is an object of the present invention to provide a satisfactory last of the latter type which will contain a minimum number of 20 parts and which, in this and other respects, will be cheap to manufacture. To this end, the invention provides a novel hinged last having a hinge plate connecting its forepart and heel part, the plate having a projection 25 engaging a spring in the forepart and being arranged to compress the spring more and more as the last is collapsed, together with joint surfaces on the two last parts, co-operating to hold them firmly against twisting 30 stresses.

These and other features of the invention comprising certain combinations and arrangements of parts will be apparent from the following description of a preferred embodiment of the invention shown in the drawings, in which

Fig. 1 is a side elevation, partly in section, of a last embodying the invention in operative extended condition; and

Fig. 2 shows the last in collapsed condition.

The illustrated last comprises a forepart 10 and a heel part 12 separated by a cut comprising an open V 14 at the top of the last. A 45 circular knuckle 16 on the forepart fits a similar circular groove 18 on the front face of the heel part, the knuckle and groove being connected by steps 20 to short vertical opposed faces 22 which run out into the bottom of the last. The steps 20 hold the last parts firmly against twisting stresses. Vertical kerfs 24, 26 are sawed into the meeting faces of the forepart and the heel part, and a hinge plate 28 is mounted fixedly in 50 the heel part by means of two pins 30, 32,

extending through the heel part from side to side. A third pin 33 located at the center of the knuckle 16-18 passes through the forepart and the lower front corner of the plate 28, thus furnishing a pivot around 60 which the heel part and its attached plate 28 swing in collapse.

The upper front corner 34 of the plate 28 is undercut to form a shoulder 36 which rests against a headed pin 38 having its shank located within a spiral spring 40 arranged to be compressible in a hole 42 communicating with the kerf 24 in the forepart. The shoulder 36 is sufficiently long so that it remains in contact with the pin 38 at all times as it 70 swings around the pin 32 in the collapsing movement. Therefore the restoring force of the spring 40, tending to extend the last, increases continually as the collapsing movement proceeds, so that the last will immediately snap back to extended position when the collapsing stress is removed.

Having thus described my invention, what I claim as new and desire to secure by Letters Patent of the United States is:

An impositive lock hinge last comprising a forepart, a heel part having a cylindrical recess in its front face, a knuckle of cylindrical outline formed on the rear end of the forepart and arranged to fit into the said 85 circular recess, a horizontal shoulder on each said last part connected with the lower ends of said cylindrical surfaces respectively and extending rearwardly therefrom, co-operating vertical faces, one on each last part, extending from the rear ends of the shoulders to the bottom of the last, the heel part and forepart respectively being provided with diverging flat surfaces extending from the upper ends of said cylindrical surfaces respectively to the upper surface of the last, the opposed faces of the forepart and the heel part having each a vertical kerf formed therein and the forepart having a cylindrical hole extending downwardly and forwardly 90 from the kerf in the forepart into the instep portion of the forepart, a substantially rectangular hinge plate fixedly anchored in the kerf in the heel part and extending into the kerf in the forepart, the hinge plate having 100 a hole positioned opposite the center of the cylindrical knuckle in the forepart and having an upper corner provided with a forwardly extending shoulder, a hinge pin at the center of the knuckle in the forepart and ex- 110 116

tending through the said hole to connect the last parts pivotally, a spiral spring located in the first mentioned hole, and a headed pin having its shank located in the axis of the 5 spring and abutting against the shoulder on the hinge plate, the shoulder being of length sufficient to remain continuously in contact with the pin as the heel part swings about the

hinge pin and being arranged to compress the spring progressively as the heel part 10 swings on the hinge pin during collapsing movement of the last parts.

In testimony whereof I have signed my name to this specification.

CARL L. STURGIS.
